UNITED STATES PATENT OFFICE.

ROY C. PALMER, OF NEVADA, MISSOURI.

MARKER.

1,310,369.

Specification of Letters Patent. Patented July 15, 1919.

Application filed December 10, 1918. Serial No. 266,113.

To all whom it may concern:

Be it known that I, ROY C. PALMER, a citizen of the United States, residing at Nevada, in the county of Vernon and State 5 of Missouri, have invented new and useful Improvements in Markers, of which the following is a specification.

This invention is an improved device for use as a grave marker and the like, the 10 object of the invention being to provide an improved marker which embodies a casing to contain a card or label and having a glazed opening through which said card or label is displayed, and also having means 15 to effectually protect the card or label from the weather.

With the above and other objects in view, the invention consists in the construction, combination and arrangement of devices 20 hereinafter described and claimed.

In the accompanying drawings:

Figure 1 is a front elevation of my improved grave marker.

Fig. 2 is a vertical transverse sectional view of the same.

Fig. 3 is a longitudinal sectional view of the same.

My improved marker comprises a stake 1, the lower end of which is adapted to be driven into the ground and a casing 2 at the upper end of the stake to contain and display an identifying card, label or the like 3. The casing comprises a front 4, which is preferably made of suitable sheet metal and which is here shown as having straight upper and lower horizontal edges 5 and downwardly converging ends 7. The upper and lower edges 5 of the front are bent reversely on the rear side of the front, 40 and one end of the front is also provided with a rearwardly bent edge 6 which is united, at two of the corners of the front, to the edges 5 and is preferably soldered or otherwise secured thereto. At the opposite end of the front is an integral tab 7 which can be bent over the back of the front. The front has a centrally arranged display opening 8 and a glass pane 9 to cover said opening. Said glass pane is arranged in 50 the rear side of the front and in a recess 10 which is formed by a struckup or offset forwardly projecting portion 11 with which the front is provided and which extends around said opening.

The back 12 of the casing or card holder 55 is also made of sheet metal, corresponds in shape with the front and is a size adapting it to slide in the grooves formed by the rearwardly bent edges 5, 6 of the front, as will be understood. The back also has a forwardly embossed or stamped central portion 13 which is adapted to enter the recess in the rear side of the front and on which boss the identifying card or label is pasted, so that said card or label is held firmly and 60 directly against the rear side of the glass pane and said glass pane is also firmly held in place. When the card or label has thus been arranged and the front has been thus arranged in place on the back, the front 70 is firmly locked to the back and cannot become casually detached therefrom.

Owing to the construction of the front with the chambered card displaying offset and the construction of the back with the 75 embossed card holding portion and owing to the construction of the front with the turn back edges which engage around the sides of the back, the card is securely and effectively protected from the weather and can- 80 not be injured by rain.

While I have herein shown and described a preferred embodiment of my invention, I would have it understood that changes may be made in the form, proportion and construction of the several parts without departing from the spirit of my invention and within the scope of the appended claim.

Having thus described my invention, I 90 claim:

In a marker of the class described, a casing comprising a metallic sheet having its upper, lower and one side edge bent rearwardly and connected together to define grooves, said sheet having an enlarged central display opening and an outstruck portion surrounding said opening, a plate of similar contour as that of the sheet slidably fitted in said grooves from the remaining side of the sheet, and a bendable tongue carried by the latter mentioned side edge of the sheet and adapted to be arranged against the rear of said plate.

In testimony whereof I affix my signature.

ROY C. PALMER.
